CLAIM

The ornamental design for a display with icon for oral-care appliance, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a first embodiment of the display with icon for oral-care appliance;

FIG. 2 is a front view thereof;

FIG. 3 is a right-side view thereof;

FIG. 4 is a rear view thereof;

FIG. 5 is a left-side view thereof;

FIG. 6 is a top plan view thereof;

FIG. 7 is a bottom view thereof.

FIG. 8 is a perspective view of a second embodiment of the display with icon for oral-care appliance;

FIG. 9 is a front view thereof;

FIG. 10 is a right-side view thereof;

FIG. 11 is a rear view thereof;

FIG. 12 is a left-side view thereof;

FIG. 13 is a top plan view thereof;

FIG. 14 is a bottom view thereof.

FIG. 15 is a perspective view of a third embodiment of the display with icon for oral-care appliance;

FIG. 16 is a front view thereof;

FIG. 17 is a right-side view thereof;

FIG. 18 is a rear view thereof;

FIG. 19 is a left-side view thereof;
FIG. 20 is a top plan view thereof;
FIG. 21 is a bottom view thereof.

FIG. 22 is a perspective view of a fourth embodiment of the display with icon for oral-care appliance;

FIG. 23 is a front view thereof;

FIG. 24 is a right-side view thereof;

FIG. 25 is a rear view thereof;

FIG. 26 is a left-side view thereof;

FIG. 27 is a top plan view thereof;

FIG. 28 is a bottom view thereof.

FIG. 29 is a perspective view of a fifth embodiment of the display with icon for oral-care appliance;

FIG. 30 is a front view thereof;

FIG. 31 is a right-side view thereof;

FIG. 32 is a rear view thereof;

FIG. 33 is a left-side view thereof;

FIG. 34 is a top plan view thereof;

FIG. 35 is a bottom view thereof.

FIG. 36 is a perspective view of a sixth embodiment of the display with icon for oral-care appliance;

FIG. 37 is a front view thereof;

FIG. 38 is a right-side view thereof;

FIG. 39 is a rear view thereof;

FIG. 40 is a left-side view thereof;

FIG. 41 is a top plan view thereof; and,

FIG. 42 is a bottom view thereof.

The broken line at the periphery of the figure illustrates the display and the remaining broken lines illustrate portions of the oral-care appliance. None of the broken lines form part of the claimed design.
